ICE CUBE TRAY

Thomas J. Morton, Jr., Evansville, Ind., assignor to Hoosier Lamp & Stamping Corporation, Evansville, Ind., a corporation of Indiana

Application August 8, 1936, Serial No. 94,899

7 Claims. (Cl. 62—108.5)

My invention relates to trays, and especially to metal trays of the type used as ice-cube trays in refrigerators. Such trays are customarily formed with a single sheet-metal stamping having an outwardly directed peripheral flange which, across the front end of the tray, is provided with a down-turned lip serving as a handle to aid in the withdrawal of the tray from the evaporator. In the absence of especial care in the manufacture of such trays, the down-turned lip is apt to possess burrs or sharp edges which constitute an obvious disadvantage; and, as the tray is usually formed of metal having a high heat-conductivity, the handle is disagreeably cold to the touch.

It is the object of my invention to provide a tray of the type above described with a handle member which will cover the free edge of the down-turned lip and which will thus prevent injury from sharp edges or burrs. A further object of my invention is to enhance the appearance of the tray by providing a handle member which can be in a contrasting color. Still another object of my invention is to provide for the tray a handle of materially lower heat-conductivity than the material of the tray, whereby the handling of the tray is rendered less unpleasant.

In carrying out my invention, I form the tray proper as above set forth—namely, with an outwardly projecting flange which, across the front end of the tray, is bent downwardly to form a lip—and I provide for this lip a handle member. The handle member is conveniently formed of some moldable material such as a synthetic resin or allied substance, and has, in plan, the same shape as the lip on the tray. The handle member is deeply grooved longitudinally for the reception of the lip, and preferably engages both the inner and outer faces of the lip tightly. If desired, the handle member may be provided at intervals with ribs, bridging the groove, such ribs being tightly received in notches in the lower edge of the lip.

The accompanying drawing illustrates my invention: Fig. 1 is a fragmental plan view of the front end of an ice-cube tray with a part thereof broken away; Fig. 2 is a fragmental side elevation of the tray shown in Fig. 1, the extreme front end of the tray and the handle member being broken away on or about the longitudinal center-line of the tray; Fig. 3 is a front elevation of the tray with a portion of the handle member broken away; and Fig. 4 is a fragmental view similar to Fig. 3, but on an enlarged scale.

The tray 10 shown in the drawing has side walls

11 and end walls 12, only the front one of which is shown. The metal of the tray is formed to provide a peripheral flange 13 which, across the front end of the tray, as indicated at 14, may be somewhat wider than at other portions. The front edge of the widened flange 14 is bent downwardly to provide a lip 15 which, in the conventional tray, is used as a handle.

The handle member 16 applied to the lip 15 in accordance with my invention is, as above set forth, preferably made of a synthetic resin or some other suitable moldable material. I prefer cellulose acetate. In plan, the handle member 16 has the same shape as the lip 15 and is provided with a relatively deep groove for the reception of such lip. The groove should preferably have a width closely approximating the thickness of the lip in order that the side walls of the groove will frictionally engage the sides of the lip when the handle member is in place.

While the handle member might be held in place with sufficient permanence merely by the frictional engagement between the walls of the groove and the sides of the lip 15, or while it could be cemented in place, I prefer to employ other means for insuring that it will not be easily removable. To this end, I form the handle member with one or more transverse ribs 17 which extend between the walls of the groove in the handle member and which are received in notches 18 in the lower edge of the lip 15. The notches are of such a width that their side edges firmly embrace the respectively associated ribs 17 and augment the effect of friction between the side walls of the groove and the sides of the lip in holding the handle in place. I find it convenient to make the notches 18 of a dove-tail shape with the distance across the throat of the dove tail a few thousandths of an inch less than the thickness of the associated rib 17.

In attaching a handle member of the type described, it is brought into place below the lip with the edge of the lip received in the groove and with the ribs 17 aligned with the notches 18. With the handle member in this position, it is forced upwardly to cause the ribs 17 to enter the notches. In passing through the throats of the notches, the ribs 17 are compressed slightly and, expanding above such notch-throats tend to hold the handle securely in place.

Not only do the ribs 17, by co-operating with the sides of the notches 18, act directly to hold the handle 16 in place, but they also tie together and prevent any spreading of the walls of the groove in the handle and thus insure that the

groove-walls will tightly embrace the lip at all times. To this end, the ribs 17 may extend well toward the top of the groove in order to exert their tying effect close to the free edges of the groove-walls; but, for the sake of appearance, the tops of the ribs are preferably located slightly below the top of the handle member which is thereby enabled to completely conceal the notches 18.

10 I find that a handle member attached as above indicated will remain firmly in place against any ordinary dislodging force. It protects the hands of the user from injury as the result of sharp edges or burrs on the lip 15 and it is not as disagreeably cold to the touch as is the metal lip.

15 I claim as my invention:—

1. A tray formed of sheet-metal and having at one end an outwardly extending flange provided with a downturned lip, and a molded handle member generally U-shaped in cross-section embracing the lower edge of said lip, said handle member being provided with one or more integral ribs extending between its two side walls and the lower edge of said lip being provided with 20 a notch for the reception of each of said ribs, each of said notches being of dove-tail shape, and the distance across the throat of the dove-tail being slightly less than the thickness of the associated rib whereby the material of said rib will 25 be compressed when the handle is forced into place.

2. A tray formed of sheet-metal and having at one end an outwardly extending flange provided with a downturned lip, and a molded handle member generally U-shaped in cross-section embracing the lower edge of said lip, said handle member being provided with one or more integral ribs extending between its two side walls and the lower edge of said lip being provided with a notch 30 for each of said ribs, the side walls of each notch tightly embracing the associated rib.

3. A tray formed of sheet-metal and having at one end an outwardly extending flange provided with a downturned lip, and a molded handle member generally U-shaped in cross-section embracing the lower edge of said lip, said handle member having a longitudinal groove 35 receiving the lower edge of said lip, said lip being provided with one or more openings extending through it, and said handle member being provided within said groove with a projection for each of said openings and having a press fit therein.

bracing the lower edge of said lip, said handle member being provided with one or more integral ribs extending between its two side walls and the lower edge of said lip being provided with a notch for each rib, the width of each notch being slightly less than the normal thickness of its associated rib, whereby the material of each rib is compressed when the handle member is in place.

4. A tray formed of sheet-metal and having at one end an outwardly extending flange provided with a downturned lip, and a molded handle member generally U-shaped in cross-section embracing the lower edge of said lip, said handle member being provided with one or more integral ribs extending between its two side walls and the lower edge of said lip being provided with a notch for each of said ribs.

5. A tray formed of sheet-metal and having at one end an outwardly extending flange provided with a downturned lip, and a molded handle member, said handle member having a longitudinal groove in which said lip is received, and means extending through said lip and between the walls of said groove for preventing separation 20 of the groove-walls, said means being integral with the handle member.

6. A tray formed of sheet-metal and having at one end an outwardly extending flange provided with a downturned lip, and a molded handle member, said handle member having a longitudinal groove in which said lip is received, and means extending through said lip and between the walls of said groove for preventing separation 25 of the groove-walls.

7. A tray formed of sheet-metal and having at one end an outwardly extending flange provided with a downturned lip and a molded handle member having a longitudinal groove receiving the lower edge of said lip, said lip being provided 30 with one or more openings extending through it, and said handle member being provided within said groove with a projection for each of said openings and having a press fit therein.
